No. 626,907.

Patented June 13, 1899.

H. J. HEWITT.

CHANDELIER.

(Application filed Jan. 7, 1898.)

(No Model.)

UNITED STATES PATENT OFFICE.

HENRY JAMES HEWITT, OF CHICAGO, ILLINOIS.

CHANDELIER.

SPECIFICATION forming part of Letters Patent No. 626,907, dated June 13, 1899.

Application filed January 7, 1898. Serial No. 665,889. (No model.)

To all whom it may concern:

Be it known that I, HENRY JAMES HEWITT, a citizen of the United States, residing at Chicago, in the county of Cook and State of Illinois, have invented certain new and useful Improvements in Chandeliers, of which the following is a full, clear, and exact specification.

My invention relates to chandeliers or light-supports, and the improvements have more especial reference to means whereby the altitude of the light may be varied to suit the requirements of the user, thus enabling the user to draw the light down close to a table, for instance, or to elevate it out of the way, as desired.

The object of my invention is to provide an improved construction of extensible chandelier or light-support which will enable the end thereof supporting the light to be readily raised or lowered and locked at the desired elevation.

Another object of my invention is to so construct the parts of an extensible chandelier or light-support that the lower or movable part will not fall or descend violently in the event it should be accidentally released.

A further object of my invention is to provide means for locking the telescoping parts of the gas-chandelier which shall also constitute a packing for preventing the escape of gas between the telescoped members.

With these ends in view my invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is a side elevation of my improved chandelier, showing it adapted for using gas. Fig. 2 is an enlarged vertical sectional view, partly broken away, the globe being omitted. Fig. 3 is a transverse sectional view taken on the line 3 3, Fig. 2; and Fig. 4 is a view similar to Fig. 2, partly in section and partly in full, showing the construction of one of the internal tubes, the view being taken at right angles to Fig. 2.

1 represents the gas-pipe, which may be secured at the ceiling to the threaded end of the ordinary service-pipe (not shown) or at-

tached in any other suitable way to the gas-supply, and 2 represents a casing in which the pipe 1 is inserted and to the lower end of which is secured the chandelier 3 or the parts for supporting and supplying the burner or burners 4. The lower end of the pipe 1 is screw-threaded upon or otherwise attached to 60 a sleeve or collar 5, and passing upwardly through this sleeve or collar is a tube 6, provided from top to bottom with a spiral groove or channel 7, in which engages one or more studs 8, secured to the inner side of the sleeve 65 5, such studs 8, if desired, being in the form of small rollers or antifriction-wheels of less diameter than the width of the groove 7, so as to roll therein as the tube 6 is pushed up or pulled down, and thus relieve the wear 70 upon the studs. I have shown and prefer to employ two of these studs 8 on opposite sides and at opposite ends of the sleeve 5, so as to provide a more uniform bearing.

The lower end of the tube 6 is reduced in 75 diameter, as clearly shown in Fig. 2, and carried downwardly through and swiveled in a collar 9, which latter is secured to the lower end of the casing 2 by means of pins or screws 10 or in any other suitable way, and the extreme lower end of the reduced portion of the tube 6 is threaded and has secured thereon a nut 11, which takes its bearing under the collar 9, and thus swivels the tube 6 to the casing 2 in such a manner that the tube 6 and 85 casing 2 will be compelled to rise and fall together and at the same time allow the tube to revolve independently of the casing 2. If desired, a leather or other washer 12 may be interposed between the nut 11 and the lower 90 end of the collar 9 to relieve the parts of wear.

The portions 3 of the chandelier are provided with a hollow head 13, from which lead the pipes for supplying the burners with gas, and the upper end of this head 13 is screw-threaded upon or otherwise attached to the lower end of the collar 9, the head 13 being of larger diameter than the nut 11, so as to permit the latter to turn. The screw 10 also serves as means for binding the head 13 and 100 casing 2 together.

The upper end of the tube 6 is provided with a flange 14, which makes such end of the tube of sufficient diameter to fit accurately within the pipe 1, with capability of sliding, and supported upon this flange 14 is a combined lock 105

and packing consisting of a normally-contracted ring 15, which is divided and has its divided ends overlapped in the manner of an ordinary steam-packing, as more clearly shown in Fig. 4. When this ring is in its normal condition, it exerts no material pressure against the walls of the pipe 1, but when expanded with sufficient force it binds against the walls and forms a solid support for the tube 6, the casing 2, and other parts of the chandelier supported thereon. In order that the ring 15 may be thus expanded when it is desired to lock the tube 6 within the pipe 1, I arrange at the upper side thereof a tooth or wedge 16, which has operative connection with an interior rod 17, connected at its lower end to an exterior operating lever or handle 18, the latter being secured to a transverse conical shaft 19, journaled in the head 13 and having eccentric or crank connection 20 with the rod 17. The tooth 16 is arranged within or directly over a notch or pair of inclines 21, formed in the upper edge of the ring 15, and when such tooth is pulled downwardly into engagement with these inclines it forces the ends of the ring in opposite directions and causes the ring to expand within the pipe 1, thus at once locking and supporting the tube 6 and preventing the escape of gas from the pipe 1 into the space between the latter and the tube 6, and thereby avoiding the possibility of the gas escaping along the channel 7 and thence to the atmosphere through the space between the pipe 1 and casing 2. The ring 15, it will be seen, is provided with a lap-joint 16^a, like a piston packing-ring, which has overlapping portions when viewed from the side, as in Fig. 4, and also overlapping portions when viewed in cross-section, as in Fig. 2.

In order that the tooth 16 may be held and guided, the upper end of the tube 6 is provided with a reduced neck 22, and the tooth 16 is formed on a ring 23, surrounding such neck and having a collar 24, attached by spider 25 and nuts 26 to the upper end of the rod 17, thus supporting the rod upon the collar 15 when the latter is expanded and at the same time affording a free passage-way for the gas down through the tube 6.

It is, of course, very evident that where electricity is used for light the wires may be extended through the pipe 1 and other gas-passages of the chandelier without departing from the spirit of my invention.

With an extensible chandelier thus constructed it will be seen that when the operating-lever 18 is turned in one direction the tooth 16 will be elevated out of engagement with the notch or inclines 21, and in thus allowing the ring 15 to contract the chandelier may be raised or lowered, as desired, and when the proper elevation is reached a turn of the lever 18 in the opposite direction will again expand the collar 15 and lock the parts together, as described. Should the lock be accidentally released, the chandelier would

descend of its own weight; but the spiral groove 7 and studs 8 would afford sufficient friction to prevent damaging shock, the upper one of the studs 8 serving, when the end of the groove 7 is reached, as a stop for preventing further downward movement.

Having thus described my invention, what I claim as new therein, and desire to secure by Letters Patent, is—

1. An extensible chandelier having in combination a fixed pipe, a hollow head to which the globe or light of the chandelier is attached, a tube swiveled in and supporting said head, said tube and pipe being provided with spiral groove and stud connection, means for locking said tube and pipe together, and a rod for operating said means extending from said head through said tube, substantially as set forth.

2. An extensible chandelier having in combination a fixed pipe, the hollow head 13 forming a support for the light or globe, a tube having a reduced end provided with a swivel connection with said head and supporting the latter, a lock for securing said pipe and tube together, an operating-rod for actuating said lock, passing downwardly through said tube and into said head, and an exterior operating-lever having operative connection with said rod, substantially as set forth.

3. An extensible chandelier having in combination a fixed pipe, a tube telescoped therein and serving as a support for the chandelier, the expansible ring arranged in said pipe and having a notch or inclines, a tooth adapted to engage with said notch or inclines for expanding said ring, and means for forcing said tooth into engagement with said notch or inclines, substantially as set forth.

4. An extensible chandelier having in combination a fixed pipe, a tube telescoped therein and serving as a support for the chandelier, a split ring arranged above said tube and supported thereon and having a notch at its intersection, a wedge or tooth arranged to engage in said notch, a vertically-movable collar to which said wedge is connected, a guide on said tube for said collar, an operating-rod arranged in said tube and guide and having spider connection with said collar and means for reciprocating said rod, substantially as set forth.

5. An extensible chandelier having in combination a fixed pipe, a tube telescoped therein, the hollow head 13 to which said tube is swiveled, the shaft 19 journaled in said head and having an operating lever or handle, means for locking said tube and pipe together and the rod 17 having connection with said means and crank or eccentric connection with said shaft said rod extending through said tube, substantially as set forth.
